THERMAL RELAY

Edwin August Miller, Fairfield, Conn.

Application October 25, 1949, Serial No. 123,338

2 Claims. (Cl. 200—122)

1

This invention relates to thermal relays—the electrical combination of a bimetal actuating member and a snap-acting switch blade.

The objects of the invention are to provide a thermal relay with a thermostatic actuating member adapted to operate a snap-acting switch blade supported at one end differentially by a second thermostatic member; to provide such thermal relay with a longitudinally shiftable switch blade; to provide such a switch blade with a spring strip actuated by said thermostatic members adjacent its longitudinal center; and to provide said differential support with an adjustable means.

With reference to the accompanying drawing the Figure 1 is a side elevation of the device illustrating movable parts in one position; Figure 2 is a similar elevation omitting electrical thermal winding of certain thermostatic structure and illustrating movable parts in relatively moved position; Figure 3 is a plan view of a thermostatic member having its forward end supported by a base and illustrating the blade member and its support in dotted lines; Figure 4 is a plan view of switch blade; Figure 5 is a rear elevation of device illustrating terminals of thermostatic members and contact arms supported by an insulation base; and Figure 6 is an enlarged detail partly in cross-section.

The thermostatic structure of the improved device is capable of performing many human-like functions with the greatest accuracy and a greater stability under vibratory conditions due to the flexibility of both layers of the top thermostatic member supporting the spring strip at an intermediate point, the said thermostatic member's main function being to snap over the switch blade and not to support the blade under tension or compression.

With particular reference to the accompanying drawing, the numeral 1 designates a supporting base of insulation material to which is secured the rear portions of both thermostatic members 2 and 3 and both contact arms 4 and 5, each of said rear portions extending beyond said support 1 to provide terminals.

Relatively spaced interfacing contacts 6 and 7 are supported, one by each of the arms 4 and 5, respectively, for engagement by either one of the blade contacts 8 or 9. The switch-blade 10, while shown having parallel outside strips 11 and 12 with relatively aligned spring strip portions 13 and 13A therebetween, may comprise, if desired, two outside spring strips with the holding blade strip therebetween or different arrangement thereof.

2

While the thermostatic members 2 and 3 are shown as comprising bimetal layers 2A—2B and 3A—3B, respectively, they of course are not intended to be limited as to the number of such layers.

The Figure 1 illustrates each of the thermostatic members 2 and 3 as having thermal windings 14 and 15, respectively, but both or either of such windings 14—15 may be dispensed with as illustrated by the Figure 2 as to one of said windings.

The thermostatic member 2 is provided with a downwardly bent extremity 16 which is provided upon its rear and forward sides with notches 17—18, said notches 17—18 being relatively positioned as shown in the Figure 1, or staggered as shown in the Figure 2.

The bent extremity 16 is movable between the parallel outside strips 11 and 12, the relatively aligned spring strip portions 13 and 13A having their abutting extremities 13B and 13C each held within a notch 17 or 18 of the bent extremity 16 of the thermostatic member 2.

The rear extremity of the switch blade 10, as illustrated by the Figure 1, is differentially held by the support 3C carried by the extremity 3D of the thermostatic member 3, such differential holding means being best illustrated by the Figure 6 as comprising the headed screw 10A the shank of which is first inserted within an enlarged perforation 10B of the blade 10 and within the coil spring 10C which intervenes between the blade 10 and the top surface 3E of the support 3C, the extremity 10D of the screw 10A being secured within the support 3C, but the said holding means may be of any similar structure, the screw 10A providing an adjustable means for tightening the tension of the spring 10C.

In operation, electrical circuits having been established, including the terminals 2C, 3D, 4A and 5A, and electrical current is applied to the extremities 14A—14B and 15A—15B of the thermal windings 14 and 15 respectively, of the Figure 1, the resulting heat therefrom will expand layer 2B of the thermostatic member 2 and layer 3A of the thermostatic member 3 whereby the extreme portions thereof 16 and 3A of the members 2 and 3, respectively, will be moved in opposite directions to the positions illustrated by the Figure 2, the blade contact 8 breaking with a snap action its engagement with the contact 6 on the arm 4 to engage the blade contact 9 with the contact 7 on the arm 5. Such snap action of the blade 10, carrying the blade contacts 8 and 9, is due to the spring strip intermediate end portions 13B and 13C (better shown by the Figure

4) pivotally engaged within the notches 17 or 18 and there providing pivot points crossing and snapping over the plane of the switch blade 10 as the rear extremity of the switch blade 10 is moved downward with the support 3C carried by the extremity 3D of the thermostatic member 3 and thereby causing the free extremity of the blade 10 to instantly move from the stop 6 to the stop 7.

The free extremity of the blade 10 having thus been thermostatically moved from its normal position illustrated by the Figure 1 to the operated position illustrated by the Figure 2, a reverse action is had when the thermostatic influence is lowered or removed from the thermostatic members 2 and 3 by which both members 2 and 3 return to their normal positions as illustrated by the Figure 1, they having completed the relay's operating cycle.

While a single thermal winding 14 or 15 is shown carried by either one of the thermostatic members 2 or 3, it is to be understood that, within the intent of the invention, there may be more than one thermal winding on each or both of the members 2 or 3, each of such thermal windings being in a different circuit, one from the other, to provide a wider latitude of control by having a greater or lesser amount of electrical current passing through either one or both windings.

I claim:

1. A thermal relay snap acting switch device comprising two relatively spaced substantially parallel arms of thermostatic metal strips, each arm having a fixed extremity separately mounted upon a block of insulation material; relatively spaced stops supported intermediate said arms by said block; an erect support carried by one of said arms adjacent the free extremity thereof; a switch blade member having one extremity mounted upon said erect support and free to move thereon longitudinally of said blade member and free to move at the other extremity between said stops; a spring strip of which the extreme ends are carried by the said blade extremities, said spring strip being normally bowed below the plane of said blade member as said free extremity of said blade member is in contact with the upper one of said stops, said bowed spring strip at an intermediate portion thereof being cut to provide two separate lengths of said strip; and a bent extremity with which the free end of the other of said thermostatic arms is provided; notches with which the said bent end is provided upon opposite surfaces thereof to receive the cut ends of the said divided spring strip; whereby upon applied heat to said thermostatic arms the free extremity of each arm will be moved in opposite directions thus to co-operate with said longitudinally movable mounting to position said cut ends of said divided spring strip above said plane of said blade member, the said

mounted extremity of which is moved downward as the said separate lengths of said divided spring strip snap with respect to said blade member to suddenly move the said free extremity thereof from said upper to the lower of said stops; and a reverse operation of said thermal relay upon the removal of said applied heat from said thermostatic arms.

2. A thermal relay snap acting switch comprising two relatively spaced substantially parallel arms of laminated thermostatic metal, each arm having a fixed extremity separately mounted upon a base of insulation material; relatively spaced stops supported intermediate said arms by said base; an erect support carried by one of said arms adjacent the free extremity thereof; a switch blade member having one extremity mounted upon said erect support and free to move thereon longitudinally of said blade member and free to move at the other extremity between said stops; said blade member having an opening therethrough; a pair of relatively opposing compression members within said opening, each of said compression members having an end carried by an extremity of said blade member, and an opposite end engaged within a notch provided therefor upon a bent extremity with which the free end of the other of said thermostatic arms is provided; said notches being normally positioned out of the plane of said blade member as said other extremity of said blade member is in contact with one of said spaced stops; whereby upon applied heat to one of said thermostatic arms to move its free extremity thus to co-operate with said longitudinally movable mounting and another of said thermostatic arms to position said notch engaged extremities of said compression members from one to the other side of the said plane of said blade member, the said mounted extremity of which is moved in a direction opposite to that of said notch engaged ends, as the said compression members move overcenter with respect to the plane of said blade member to suddenly snap-actingly move the said free extremity thereof from one to the other of said spaced stops; and a reverse operation of said thermal relay upon the lowering or removal of said applied heat from the said one of said thermostatic arms.

EDWIN AUGUST MILLER.
